UNITED STATES PATENT OFFICE.

OTIS F. REITER, OF BALTIMORE, MARYLAND.

TOY.

Application filed November 15, 1923. Serial No. 674,832.

To all whom it may concern:

Be it known that I, OTIS F. REITER, a citizen of the United States, residing at Baltimore, in the State of Maryland, have invented certain new and useful Improvements in Toys, of which the following is a specification.

This invention relates to improvements in toys for picking up stones, marbles, or other similar objects, and has for its object to provide a simple, cheap and attractive toy for the amusement of children.

The invention consists of the novel construction and arrangement of the parts and combination of parts hereinafter more fully set forth in the following specification and pointed out in detail in the appended claims.

In the accompanying drawing,—

Figure 1 is a top plan view of my invention.

Figure 2 is a section of Figure 1 taken on the line 3—3 thereof.

Figure 3 is a side elevation of Figure 2.

Figure 4 is a detail perspective view of the raker plate.

Referring to the accompanying drawing, forming part of this specification, and in which like reference numerals designate like parts throughout the several views thereof, 1 designates the side bars of the frame to the front ends of which is riveted the discharge apron 2. To the rear of the side bars 1 is riveted the upper end of the raker plate 3, the lower end of which latter is secured to the lower cross piece of the supporting piece 4. The said supporting piece 4 has its ends fitted over the screws 5 which form the axle for the wheels 6. The said wheels 6 are secured to the ends of the spindle 7 so that the said spindle revolves with the wheels. Projecting laterally from the spindle 7 are three rows of pins, or rake teeth, 8 to form a rake to lift the stones, marbles, or other similar objects and carry them up the raker plate 3 and discharge them on the straps 9 from which they pass to the apron 2 and are discharged. The said straps 9 extend around the spindle 7 between the pins, or teeth, 8 and have their ends riveted to the apron 2. A handle 10 is secured to the rear upper end of the raker

plate 3 by the metal piece 11 and has a supporting piece 12 extending down and secured to the raker plate 3 and the supporting piece 4. While I have shown and described three rows of the rake teeth 8 any desired number of rows may be employed.

The operation of the device is as follows:

Stones, marble, or other objects are placed in front of the toy and the latter pushed along by the handle 10 and as the lower edge of the raker plate 3 comes into contact with the said objects the teeth 8 on the revolving spindle will carry them up the raker plate 3 and discharge them on the top of the straps 9 from which they fall, or roll, to the discharge apron 2 and fall in front of the toy to be picked up again in the manner described. Or the toy may be used where stones are naturally found and will pick them up in the same manner.

Having thus described my invention, what I claim is:

1. A toy comprising a frame, wheels revolvably mounted in said frame and connected by a spindle revoluble therewith, a raker plate mounted rearwardly of said wheels, a plurality of rake teeth mounted on the spindle of the wheels and revoluble therewith, and a discharge apron at the front of the said wheels.

2. A toy comprising a frame, wheels revolvably mounted in said frame and connected by a spindle revoluble therewith, a raker plate mounted rearwardly of said wheels, a plurality of rake teeth mounted on the spindle of the wheels and revoluble therewith, and straps projecting between said rake teeth and having their ends secured to the frame.

3. A toy comprising a frame having a discharge apron at the front thereof, wheels revolvably mounted in said frame and connected by a spindle revoluble therewith, a raker plate mounted on said frame rearwardly of said wheels, a plurality of rake teeth mounted on the spindle of the wheels and revoluble therewith, and straps each having one end secured to said discharge apron and projecting between the rake teeth.

4. A toy comprising a frame having a discharge apron at the front thereof, a han-

dle at the rear of said frame, wheels revolubly mounted in said frame and connected by a spindle revoluble therewith, a raker plate mounted rearwardly of said 5 wheels, a plurality of rows of rake teeth projecting laterally from the said spindle and revoluble therewith, and straps each

having the ends thereof secured to the discharge apron and projecting around the said spindle of the wheels between the rake 10 teeth.

In testimony whereof I affix my signature.

OTIS F. REITER.
